TYPEWRITING MACHINE

Walter T. Sagner, West Hartford, Conn., assignor
to Underwood Elliott Fisher Company, New
York, N. Y., a corporation of Delaware

Application April 8, 1942, Serial No. 438,149

8 Claims. (Cl. 197—64)

This invention relates to typewriting and other office machines having carriages, and with regard to certain more specific features thereof to tabulating speed controls for the carriages of such machines, and also to devices in such machines for suppressing or checking rebounding of the carriages when such are intercepted incident to tabulating.

One of the objects of the invention is to provide a carriage rebound checking or suppressing device which is reliable, efficient and quiet in operation, more particularly, to provide a device of this character which is effectuated in direct response to the interception of the carriage incidental to tabulating.

It is also an object of the invention to provide rebound checking device of efficient construction, which is capable of idly storing energy during tabulating runs of the carriage and which is adapted to apply this energy for checking carriage rebounding whenever the carriage is abruptly arrested incidental to tabulating.

A further object of the invention is to provide a simple and reliably operating rebound checking or suppressing device which is self-releasing after the tendency of the carriage to rebound has subsided.

Another object of the invention is to provide a device of economic manufacture, which by application of frictional resistance suppresses rebounding of the carriage, thus avoiding objectionable shock and noise.

It is also an object of the invention to provide a device which is built in accord with any one or more of the above-noted objects and which additionally and in an efficient and reliable manner controls the speed of the carriage during tabulating runs thereof.

With these and other objects in view, the invention includes certain novel features of construction and combination of elements, the elements of which are set forth in the appended claims, and a preferred form or embodiment of which is hereinafter described with reference to the drawings which accompany and form part of this specification.

In the drawings:

Figure 1 is a side elevation of a typewriting machine embodying the present invention.

Figure 2 is a sectional plan view of a carriage-escapement mechanism, in association with the novel carriage-speed governor and rebound-checking device, the section being taken along line 2—2 of Figure 1.

Figure 3 is a perspective view showing certain

parts of the combined governor and rebound-checking device separated along a main axis thereof.

Figure 4 is a fractional side elevation of the combined carriage-speed governor and rebound-checking device in a condition governing the tabulating speed of the carriage.

Figure 5 is a view similar to Figure 4, but the device of the invention is shown in a condition to check rebounding of the carriage.

Figure 6 is a fractional perspective view of an upper end of a tabulator reed, in association with a guide plate therefor.

Figure 7 is a sectional plan view taken along line 7—7 of Figure 5, illustrating brake shoes in rebound-checking engagement with a brake drum.

Directing attention now particularly to Figure 1, a carriage 11 is adapted to travel in letter-feed and return directions upon a frame generally designated by the numeral 12. The frame embodies a transverse trackway 13 which guides a rail 14 constituting part of the carriage 11, there being anti-friction elements 15 interposed between the trackway and the rail. Each lateral end of the rail 14 carries an upright carriage end 16, and upon these ends is rotatably carried a conventional paper-supporting platen 17. A spring motor 18 supported on the frame 12 has a strap connection 21 with the carriage, by means of which it is capable to move said carriage in letter-feed direction, from left to right. Movement of the carriage, however, is normally controlled by an escapement mechanism generally designated by the numeral 22. The escapement mechanism comprises a holding dog 25 and a stepping dog 26, both carried on a rocker 23 which is pivoted on an axis 24 provided on a frame-supported bracket structure 29. As may be seen in Figures 1 and 2, the holding dog 25 is normally in engagement with a toothed escapement wheel 27, the latter of which is fast upon a shaft 28 carrying at its upper end a pinion 31 meshing with a rack 32 carried by the carriage. It will be seen that the holding dog, through said escapement wheel 27 and the parts 28, 31 and 32, normally holds the carriage against advance movement by the spring motor 18. The rocker 23 is vibrated in response to each typing operation and each word spacing operation, in a manner well known, but not shown, the escapement wheel 27 being allowed to advance a letter-feed step in response to each vibration of the rocker 23.

More extensive and fast movements of the carriage may be effected under control of a tabu-

lating mechanism presently to be described. Up on the carriage, extending parallelly thereto, there is mounted a rack bar 33 supporting a series of tabulating stops 34. These stops 34 are individually positionable transversely of the rack from idle to effective positions, the stops when effectively positioned extending about one-tenth inch below the supporting rack bar. A vertically disposed tabulator counterstop or reed 35 is normally clear of the moving paths of the effectively positioned tabulator stops 34, and, therefore, has normally no control over the carriage. The upper end of the tabulator reed, as seen in Figure 6, is guided in a slot 36 provided in a horizontally disposed plate 31, the latter comprising the top of a housing 38 which is carried in a rearwardly extending relationship by the trackway 13 of the machine frame. At the bottom, the reed 35 is articulated to the rear end of a tabulator key lever 41 which is pivoted to the frame intermediate its ends and which has a key button 42 in, or in the vicinity of, the keyboard. Operation of the tabulator lever 41 raises the tabulator reed 35 into intercepting range of the nearest effectively positioned tabulator stop to the right thereof. The extent of rise of the tabulator reed 35 is limited by a rod 43 in the housing 38, in cooperation with movement limiting abutments afforded by providing the reed 35 with a slot 44. Incidental to the depression of the tabulator key 41, the carriage is released from the control of the escapement mechanism 22, so that the spring motor 18 is enabled to propel it leftwardly until intercepted by the engagement of one of the tabulator stops 34 with the stop reed 35.

To release the carriage from the control of the escapement mechanism, for a tabulating run, the reed 35 operates a lever train comprising a lever 45 and a lever 46, the latter having a pendant arm 47 for swinging the holding dog 25 about its pivot, free of the escapement wheel 27. In Figure 4, the lever 46 is shown actuated with the result that the holding dog 25 is no longer in engagement with the escapement wheel 27. The lever 46 may be pivotally carried on an appendage 48 of the escapement bracket structure 29, whereas the lever 46 may fulcrum on a rod 51 provided in the housing 38. Springs 52 and 53, respectively, associated with the lever 45 and the tabulating reed 35, maintain the tabulating mechanism normally in an ineffective condition. Inasmuch as the tabulating run of the carriage may of considerable length, that is, of some duration, it is desirable that the reed 35, upon operation, be latched in effective position, thus relieving the operator of any necessity to sustain depression of the tabulator key 42. To this end, the reed 35 (see Figures 1 and 6) is formed with an undercut at 54, which upon raising of the reed, catches over the right edge of the slot 36 in the plate 31, it being noted that the spring 52 is arranged at an angle to swing the reed rightwardly about its point of articulation with the tabulator key lever 41. Therefore, although the operator may release the tabulator key immediately after depression, the tabulator reed 35 remains raised for the duration of the tabulation run. As the carriage is being intercepted by the engagement of an effectively positioned carriage stop 34 with the tabulator reed 35, the latter is being displaced limitedly in letter-feed direction, sufficiently to permit the reed 35 to withdraw downwardly, within the slot 36, clear of the tabulator stop, providing, however, that

the tabulator key 42 has previously been released. It should be observed at this point that, concomitant with the withdrawal of the reed 35, the carriage is restored to the control of the escapement mechanism 22, that is, that the spring 53 restores the levers 45 and 46 to the normal position of Figures 1 and 2, and thereby allows the holding dog to reassume its effective position under the influence of a spring, not shown, which 10 constantly tends to engage the holding dog with the escapement wheel.

In order that the carriage may not attain an undesirable speed during tabulating runs, it has been a common practice to associate retarding means therewith. Many forms of such means are known. Also known are devices to suppress or check rebounding of the carriage incidental to being intercepted at the end of tabulating runs, rebounding being highly objectionable in that it is liable to cause the escapement to assume control over the carriage while the latter is in a rebounded position.

The present invention embodies, in a single device, reliable means to control the tabulating speed of the carriage and to suppress or check rebounding thereof at the termination of tabulating runs. In the embodiment of the invention illustrated, this device is in the form of a centrifugal governor 56, henceforth to be described. A governor head or rotor 57 is rotatable upon an arbor 58 which is fast upon an arm 61 pivoted for movement toward and away from the escapement wheel shaft 28. There is fastened to revolve concentrically with the rotor 57, a small spiral gear 62 which is normally out of mesh with a larger spiral gear 63, the latter being fast on and unitarily revolvable with the escapement wheel shaft 28. Upon actuation of the tabulator key 42, the arm 47 of the lever 46, as hereinbefore stated, swings forwardly and disengages the holding dog 25 from the escapement wheel 27. Simultaneously, the rotor carrying arm 61 is urged toward the said large gear 63 by the arm 47, through the intermediary of a spring 64. This results in the engagement of the small gear 62 with the large gear 63, as illustrated in Figure 4. The normal position of the rotor carrying arm 61 is determined by the normal position of the lever 46, the spring 64 being effective to draw the arm into contact with the pendant lever arm 47. Since operation of the arm 47 also causes the release of the carriage from the escapement, it follows that, during the ensuing carriage run, the rotor 57 is rotated. The direction of the spiral teeth on the gears 62 and 63 is such that the small gear 62, while being rotated during tabulating runs, is thrust downwardly against the supporting arm 61. Flyweight arms 65 are pivotally mounted upon the rotor 57 to swing by centrifugal force outwardly against a tapered braking drum 66 which is carried concentrically on the arbor 58, the drum having a flanged end 67 provided with a threaded socket whereto a threaded portion of the arbor extends, a lock nut 68 being adapted to be drawn up against the flange to clamp the drum securely to the arbor. Preferably, each flyweight arm 65 has imbedded in a groove a friction shoe 71 of a suitable material, the shoe having a curved braking face of considerable extent. When the carriage is at rest, the flyweight arms 65 may be touching each other as at 72, see Figure 2, and consequently the shoes 71 are out of braking contact with the drum. 75 During tabulations, as the rotor 57 is being driv-

en, the flyweights 65 swing outwardly so that the shoes 71 press outwardly against the drum and thereby exert a drag on the carriage. The critical speed at which the carriage is maintained by the governor can be regulated by screwing the tapered drum toward or away from the flyweights, the effect being to increase or decrease the effective diameter of the drum 66 and to cause thereby the shoes to engage the drum at different points from the flyweight fulcrums. The leverage at which the flyweights may act upon the drum is thus changed and the result is that the tabulating speed of the carriage can be regulated. When the carriage is intercepted by the tabulator reed 35, the spiral gear 63 is brought to an abrupt stop, but the rotor 57, by having some capacity for axial displacement away from the arm 61, is momentarily allowed to continue movement by its power of momentum along an upwardly spiraling path governed by the teeth of the spiral gear 63. The gear 62 is thus deflected upwardly until the friction shoes 71 on the flyweights become firmly wedged against the interior of the drum 66, see Figures 5 and 7, providing thereby for momentary rebound checking of the carriage; the action of the governor to this end is substantially instantaneous, that is, the friction shoes 71 engage the drum substantially before the rebounding force is set up in the carriage. Furthermore, a relatively small force is sufficient to cause the device to check rebounding because of the acute wedging angle and because the braking action is applied to a member that moves much faster than the carriage itself. It should also be observed that, inasmuch as the speed of the rotor is faster than the carriage, the rotor spirals very quickly to rebound checking position. Further of benefit is the fact that any rebounding movement of the carriage that might occur has a tendency to wedge the flyweights into firmer engagement with the tapered face of the drum. A split ring 75 sprung into a circumferential groove on the arbor 58, see Figures 1 and 5, retains the governor head against removal from the arbor when the brake drum 66 is removed. Otherwise, the split ring serves no function. Preferably, as hereinbefore pointed out, the holding dog 25 automatically assumes control over the carriage at the termination of the tabulating run of the carriage, incidental to a slight leftward displacement of the tabulator reed 35. The spring 53 at such time restores the lever 46 to the normal position seen in Figure 1, thereby effecting a separation of the gear 62 from the gear 63, the carriage being then restored to the control of the escape mechanism. The taper of the drum 66 is such that the flyweights will separate from the drum when the gears become unmeshed, or, at least, upon commencement of the next tabulating run of the carriage, it being remembered that the tendency of the gear 63 is to draw the rotor 57 downwardly during tabulations.

While the invention provides, in a single device, very efficient means to control the carriage in its tabulating travel, and to check its rebounding, it is to be understood that the device may be built solely to check or prevent rebounding. For example, the friction shoes 71 may be fixed directly to the rotor 57.

As can be seen in Figure 2, the rotor carrying arm 61 has a stop ear 73 which prevents the gears 62, 63 from being meshed too tightly. Furthermore, in order to give the arm 61 a firm support against flexure or displacement in the di-

rection of the rotor axis, the swinging end of the arm is guided between a portion of the escapement frame structure 29 and the head of a screw 74 carried on the said structure.

An important feature of the invention resides in that, that the rebound-checking action is brought about automatically by the arrest of the carriage, no matter by what tabulating means, the arrest of the carriage may be brought about. 10 It may, therefore, be seen that the invention is especially advantageously applicable to a machine embodying a series of selectively projectable tabulating counterstops, such as are used, for example, for decimal tabulating and column-selecting tabulating.

What is claimed is:

1. In a machine of the class described having a carriage, means to tabulate the carriage, carriage-intercepting means, a rotatable spiral gear having a momentum accumulating mass associated therewith and having capacity for axial movement, means limiting the axial movement of said spiral gear in one direction, means for rotating said spiral gear during tabulations, including spiral-gear means so cooperative with said spiral gear that during tabulations said spiral gear is rotated in a position thrust against said limiting means, said spiral-gear means being arrested concomitant to the interception of

30 the carriage, but said spiral gear being adapted to continue rotation by momentum in a spiraling path, away from said limiting means, by reacting against the arrested spiral-gear means, and means rendered effective by the spiraling 35 movement of said spiral gear to check rebounding of the carriage.

2. In a machine of the class described having a carriage; means to tabulate the carriage, carriage-intercepting means, a rotatable spiral gear having a momentum-accumulating mass associated therewith and having capacity for axial movement, means limiting the axial movement of said spiral gear in one direction, means for rotating said spiral gear during tabulations,

40 including spiral-gear means so cooperative with said spiral gear that during tabulations said spiral gear is rotated in a position thrust against said limiting means, said spiral-gear means being arrested concomitant to the interception of the carriage, but said spiral gear being adapted to continue rotation by momentum in a spiraling path, away from said limiting means, by reacting against the arrested spiral-gear means, a 45 brake drum, and means forced into frictional engagement with said brake drum by the rotation of said spiral gear in the said spiraling path.

3. In a machine of the class described having a carriage; means to tabulate the carriage, carriage-intercepting means, a carriage-speed governor comprising, a non-rotative member, a rotatable gear element having capacity for axial movement, means limiting axial movement of said gear element in one direction, and braking means on said gear element adapted to be forced 50 into braking contact with said member by centrifugal action, said braking means being also adapted to be forced into braking contact with said member by axial displacement of said gear element away from said limiting means, and means being carriage driven during tabulation, to rotate said gear element, the teeth of said gear element and said gear means being designed 55 to cause a deflection of said gear element in response to the interception of the carriage, axially away from said limiting means, the gear

60

65

70

75

element during this deflection being moved by momentum, whereby said braking means in association with said member checks rebounding of the carriage.

4. In a machine of the class described, stop means, means including gear means movable for interception by said stop means, momentum-storing means comprising a gear rotatable by said gear means during movement of the movable means for interception, said gear having capacity for deflection in one axial direction from a normal location and the teeth of said gear and gear means being so formed that said gear will be axially deflected under the power of momentum upon the interception of said gear means, and means responsive to the deflection of said gear means to check rebounding of said movable means when intercepted.

5. In a machine of the class described, stop means, means including gear means movable for interception by said stop means, a centrifugal governor for controlling the speed of said movable means, a gear rotatable by said gear means to drive said governor, said gear having capacity for deflection in one axial direction from a normal location, and the teeth of said gear and said gear means being so formed that said gear will be axially deflected under the power of momentum upon the interception of said gear means, said governor being so constructed as to be rendered effective to check rebounding of said movable means responsive to the deflection of said gear.

6. In a machine of the class described having a carriage, means conditionable for imparting tabulating movement to the carriage, tabulator stop-means conditionable to intercept the carriage, momentum-accumulating means comprising a rotatable gear, means comprising gear means for rotating said gear during tabulations, said gear being normally out of mesh with said gear means, and means operable to condition both said conditionable means and to mesh said gear and said gear means, whereby during the ensuing tabulation said gear is rotated, said gear having capacity for deflection in one axial direction from a normal location and the teeth of said

gear and said gear means being so formed that, upon the interception of the carriage, the said gear will be axially deflected by power of momentum, and means responsive to the deflection of said gear to check rebounding of said carriage.

5. In a machine of the class described having a carriage, means conditionable for imparting tabulating movement to the carriage, tabulator stop-means conditionable to intercept the carriage, a centrifugal governor for controlling the tabulating speed of the carriage, including, a rotor and a gear unitarily rotatable with said rotor, carriage-driven gear means, said gear and gear means being normally out of mesh, and means to condition both said conditionable means and concomitantly to mesh said gear and gear means, whereby during tabulation said governor controls the speed of the carriage, said gear and said rotor having capacity for deflection in one axial direction from a normal location and the teeth of said gear and said gear means being so formed that, upon the interception of the carriage, the said gear will be axially deflected by power of momentum, the said governor being so constructed as to become effective to check rebounding of the carriage to the said deflection of said gear.

7. In a machine of the class described having a carriage, means to tabulate the carriage, carriage-intercepting means, a conical brake-drum, a rotatable gear, carriage-driven gear means to rotate said gear, a governor head rotatable unitarily with said gear, friction shoe means on said head adapted to be thrown radially into contact with said drum by centrifugal action, thereby to control the tabulating speed of the carriage, said gear and head having capacity for deflection axially toward the smaller end of said drum, such deflection being adapted to bring the friction shoe means into braking engagement with said drum independently of centrifugal action, the teeth of said gear and gear means being of such form that, upon interception of the carriage, said gear becomes automatically deflected axially toward the smaller end of the drum, thereby to check rebounding of the carriage.

WALTER T. SAGNER.

CERTIFICATE OF CORRECTION.

Patent No. 2,340,491.

February 1, 1944.

WALTER T. SAGNER.

It is hereby certified that error appears in the printed specification of the above numbered patent requiring correction as follows: Page 3, second column, line 37, claim 2, for "taubuate" read --tabulate--; page 4, first column, line 14, claim 4, and line 28, claim 5, strike out the word "the"; and second column, line 26, claim 7, after "carriage" insert --responsive--; and that the said Letters Patent should be read with this correction therein that the same may conform to the record of the case in the Patent Office.

Signed and sealed this 25th day of April, A. D. 1944.

Leslie Frazer

(Seal)

Acting Commissioner of Patents.
